INTERNAL COMBUSTION ENGINE

Alfred Bokemüller, Gaggenau, Baden, Germany,
assignor to Daimler-Benz Aktiengesellschaft,
Stuttgart-Untertürkheim, Germany

Application April 2, 1936, Serial No. 72,255
In Germany April 4, 1935

20 Claims. (Cl. 123—65)

My invention relates to internal combustion engines of the two-cycle type and has for its object to improve the scavenging operation and to obtain an increased efficiency.

- 5 More particularly, my invention relates to two-cycle engines in which the inlet and the outlet ports are provided in the cylinder walls and are controlled by the piston and by a tubular sleeve surrounding the same.
- 10 I attain the objects of my invention by controlling the relative motion of the piston and the control sleeve in such a manner that the timed relationship of the instants at which the inlet and outlet ports are opened and closed by
- 15 the piston and the sleeve is non-symmetrical relative to the instant of the passage of the piston through its lower dead center point, the interval between the opening of the outlet and the dead center instant being larger than the interval
- 20 between the dead center instant and the closing of the outlet and/or the interval between the opening of the inlet and the dead center instant being shorter than that between the dead center instant and the closing of the inlet. Preferably,
- 25 the control of the inlet and outlet ports is so timed that the outlet is opened before the inlet is opened and that the outlet is closed shortly before or substantially together with the inlet.

A highly efficient scavenging operation will be attained by the provision of two groups of inlet ports which are controlled in a differently timed manner, one group of inlet ports being controlled by the piston only, whereby the timed relationship of the instants of opening and closing is symmetrical relative to the instant of the lower dead center position of the piston, and the other group of inlet ports being controlled by the combined function of the piston and the control sleeve so as to be left open after the first group has been closed.

40 My invention is equally applicable to machines of the Diesel type in which a liquid fuel is injected into the cylinder which is charged with air or to engines of the type in which a gaseous or vaporized fuel is compressed in the cylinder.

45 Experience has shown that the average effective pressure attainable in two-cycle engines is limited, when the inlet and outlet ports provided in the cylinder walls are solely controlled by the piston with a timed relationship of the instants of the opening and closing which is symmetrical with regard to the lower dead center instant. This applies particularly to automotive engines which are designed to produce as high a torque

50 as possible over a large range of speeds. As the

interval between the opening of the outlet and the dead center instant in such machines equals the interval between the dead center instant and the closing of the outlet, any reduction of the first interval will equally reduce the second interval and will thus adversely affect the efficiency of the scavenging operation. On the other hand, any increase of these intervals reduces the effective stroke and involves a loss of fresh charge.

5 10 A higher effective pressure has been attained with two-cycle engines in which one or more valves are used to control the scavenging operation, the scavenging air rinsing the cylinder from one end thereof to the other.

15 By the non-symmetrical control as above explained I secure an efficient scavenging operation and a high average effective pressure by simple means, a single control sleeve only being provided and the inlet and outlet ports being located in the cylinder walls close to the lower dead center point which is of particular advantage for the control of the inlet and outlet ports in high speed engines.

20 25 The provision of a plurality of groups of inlet ports has the further advantage that the control thereof may be differently timed in a simple manner and that a plurality of scavenging currents of different directions or different pressures may be produced in a suitable succession, whereby separate currents of air or gas may be used for 30 scavenging the cylinder and for charging it.

25 30 Further objects of my invention will appear from the description following hereinafter and the features of novelty will be pointed out in the claims.

35 A preferred embodiment of my invention is illustrated in the drawings.

Fig. 1 shows a partial axial section through a cylinder of the machine illustrating a part of the crank shaft and the means for operating the 40 piston and the control sleeve, the section being taken along line 1—1 of Fig. 2;

Fig. 2 is a section taken along line 2—2 of Fig. 1 and

45 Figs. 3 to 8 are diagrams illustrating the relative positions of the cylinder, the control sleeve and the piston in successive instants.

Fig. 9 shows a partial axial section through the cylinder illustrating a second form of the 50 inlet port.

Fig. 10 shows a partial axial section through the cylinder illustrating the main inlet port of the engine.

In Fig. 1, the cylinder *g* provided with the customary cooling jacket *10* supports on its

upper end a cylinder head or cover 11 which has a cylindrical downward projection 12. This projection is slightly spaced from the inner wall of the cylinder *g* so as to define an annular gap 13 therewith. A fuel-injecting mechanism 14 which may or may not include a pre-combustion chamber is inserted in the cylinder 11 in central position to inject liquid fuel into the highly heated air compressed in the cylinder. The air is fed 10 into the cylinder from a source of compressed air, such as a scavenging pump (not shown) through two groups of inlet ports *e* and *e'*, when the piston *k* approaches its lower dead center position.

15 Substantially at the same time the outlet ports *a* are opened. It will be noted from Fig. 2 that the inlet ports *e* and *e'* traverse the cooling jacket 10 and the cylinder *g* and have the general directions indicated by the arrows in Fig. 2. These arrows converge towards a point *m* which is eccentrically located in the cylinder remote from the outlet ports *a*. Preferably the inlet ports *e* and *e'* are substantially radially directed to the axis of the cylinder, as shown in Fig. 1, or these ports may be slightly upwardly directed at an acute angle with the axis of the cylinder *g*, as shown in Figs. 9 and 10. Moreover, it will be noted that the main inlet ports *e* are located at a slightly lower level than the auxiliary inlet 25 ports *e'* and that the outlet ports *a* are substantially radially directed and diametrically opposed to the ports *e'*. Some of the ports are controlled by the combined function of the piston *k* and of a sleeve valve or slide *s* which is guided within 30 the cylinder. The upper end of the slide projects into the annular gap 13 and its lower end is provided with two diametrically opposed trunnions 15. Intermediate its ends the slide *s* is provided with two groups of openings *e's* and *a's*, the openings *e's* cooperating with the inlet ports *e'* and the openings *a's* with the outlet ports *a*. Moreover, the slide is provided with two longitudinal slots *r* extending from its lower end upwardly approximately to the level of the upper 40 walls of the openings *e's*. It will be obvious, however, that the slots *r* need not extend all the way to the bottom of the sleeve *s* but may be cut off near the bottom to form rectangular openings. These slots *r* straddle the mouths *h* of the ports *e* which project inwardly from the cylinder *g* for 45 direct cooperation with the piston *k*. As will be seen from Fig. 10, the mouths *h* are of such a form that piston *k* in its lower dead center position will still be in contact therewith.

50 If desired, these projecting mouths *h* may be made separate from the cylinder *g* and suitably inserted therein for easy manufacture although they are shown integral with the cylinder in the drawings. The section of the crank shaft which is allotted to the cylinder shown in Fig. 1 is provided with three crank pins. The central crank pin 20 is connected with the piston *k* by the customary connecting rod 21 while the two other crank pins are connected with the trunnions 15 by auxiliary connecting rods 22. Preferably, the crank pin 20 is displaced from 130 to 180 degrees in advance of the two lateral crank pins to secure the proper timing of the control slide *s* relative to the piston *k*.

55 The slots *r* must be so dimensioned with reference to the stroke imparted to the reciprocating sleeve *s* by the cranks and the connecting rods 22 that the mouths *h* will not interfere with the upper walls of the slots *r*. If desired, rectangular 60 openings may be substituted for the slots *r*, as

previously described. The piston *k* is guided by the sleeve *s*.

65 The openings *a's* and *e's* cooperate with the upper end of the piston in controlling the outlet ports *a* and the auxiliary inlet ports *e'*, the control sleeve *s* moving substantially in a direction opposite to that of the piston. The opposite motion of the piston and the control slide or sleeve has the advantage that the ports are fully opened and fully closed at a higher speed.

70 The main inlet ports *e*, however, are controlled solely by the piston independently of the motion of the control slide or sleeve *s*.

75 The operation will be explained hereinafter with reference to the diagrams shown in Figs. 3 to 8 which illustrate successive instants during one revolution of the crank shaft. In Fig. 3 the elements assume the position in which the opening of the outlet ports *a* commences. The crank pin 20 operating the piston is in the position *A*₁ and the crank pins operating the control sleeve 20 in the position *B*₁.

80 It will be noted that the point *A*₁ is ahead of the point *B*₁ by the angle *B*. This angle may be chosen from 130 to 180 degrees. The piston moves downwardly and the control sleeve upwardly. Therefore, the outlet ports *a* will be very quickly uncovered by the upper edge of the piston and by the opening *a's* of the control sleeve. The main inlet ports *e* are still covered by the 30 piston and the auxiliary inlet ports *e'* by the control sleeve.

85 Fig. 4 illustrates the instant at which the main inlet ports *e* are uncovered by the upper edge of the piston, the main crank having arrived at *E*₁.

90 Fig. 5 shows the instant at which the opening of the auxiliary inlet ports *e'* by the sleeve opening *e's* commences, the main crank arriving at *E*₁' shortly after having passed the lower dead center position *UT*. At this time, the sleeve *s* is rapidly moving downwardly, whereby the auxiliary inlet ports *e'* will be uncovered within a short interval while the outlet ports *a* are being closed. The main inlet *e* is fully opened.

95 The closing of the outlet ports is effected by the opposite motion of the downwardly moving sleeve and of the upwardly moving piston. The end of the closing operation is illustrated in Fig. 6. In this instant, the crank has arrived at 50 the point *A*₂. The main inlet ports *e* are partly covered again by the piston, whereas the auxiliary inlet ports are being uncovered by the opening *e's*.

100 Shortly afterwards, the elements arrive at the position shown in Fig. 7 in which the crank passes through the point *E*₂. At this instant, the main inlet ports *e* have just been completely covered by the piston *k*, whereas the auxiliary inlet ports *e'* are just fully opened.

105 In Fig. 8 the crank arrives at the point *E*₂'. At this instant, the auxiliary inlet ports *e'* are fully closed. As the upward motion of the piston and the downward motion of the sleeve are comparatively rapid, the auxiliary inlet ports *e'* were closed at a high speed. This has the advantage, that the full cross-section of the auxiliary inlet ports *e'* is kept open until shortly before the closing begins, namely until the instant of Fig. 7, 70 whereby a very effective scavenging or charging or supercharging operation is rendered possible without delaying the closing of the auxiliary inlet to such an extent that the scavenging or charging medium entering therethrough would 75

meet with a considerable counteracting compression pressure.

In Fig. 6 the entire control diagram is shown with reference to the crank circle. It will be noted that the interval between the instants A_1 and UT is larger than the interval between the instants UT and A_2 which means that the outlet ports are opened sooner with reference to the lower dead center point than they are closed. Inversely, the interval between E_1 and UT is shorter than the interval between UT and the instant E'_2 at which all of the inlet ports are completely closed. Therefore, the outlet diagram $A_1-A_2=\alpha$ and the inlet diagram $E_1-E'_2$ overlap in a favorable manner, as is shown in Fig. 6.

The inlet diagram is obtained by the control diagram $E_1-E_2=\epsilon$ of the main inlet ports situated symmetrically relative to the lower dead center point of the piston and by the control diagram $E'_1-E'_2=\epsilon'$ of the auxiliary inlet ports situated very non-symmetrically relative to the dead center point.

The main inlet ports may serve to scavenge the cylinder, whereas the auxiliary or additional inlet ports are used in the main for charging and supercharging the cylinder. The charging medium may be any suitable fluid such, for example, as air, when the invention is applied to Diesel engines, or a gas or a fuel mixture when the invention is applied to machines provided with a carburetor. In the two latter cases the gas or fuel mixture may be fed to the cylinder through the auxiliary inlet ports, whereas pure scavenging air is fed to the main inlet ports. Moreover, the pressure at which the air charge enters through the main or auxiliary inlet ports may be made different by suitably choosing and dimensioning the sources supplying the scavenging medium.

In the embodiment illustrated in the drawings, provision is made for a supercharging of the cylinder through the auxiliary inlet ports. However, the control points A_1 , A_2 , E_1 , E_2 , E'_1 , E'_2 may be so arranged relative to each other that E'_2 coincides with A_2 or that A_2 is preceded by E_2 and E'_2 without departing from the above described principal relation of the inlet or outlet intervals.

In view of the low position of the control openings, the sleeve may be so designed that it terminates substantially in the level of the openings a_s and e_s and does not engage the gap 13.

Further modifications will readily appear to anyone skilled in the art.

What I claim is:

1. In a two-cycle internal combustion engine, comprising in combination, a cylinder, a piston in said cylinder, a slide valve in said cylinder, a tubular sleeve having cooperating openings guided for reciprocating movement in said cylinder, a piston guided for reciprocating movement in said sleeve, a crank shaft having a plurality of crank pins and a plurality of connecting rods one of which joins one of said crank pins to said piston and the other of which joins the other crank pins to said sleeve, said piston operating crank pin leading said sleeve operating crank pins by approximately 130 to 180° , whereby said inlet and outlet ports are controlled asymmetrically with respect to the lower dead center point of said piston, the outlet ports being opened sooner with respect to said dead center point than they are closed and the inlet ports being opened later with respect to said dead center point than they are closed.

2. The combination according to claim 1 including means for introducing a stream of charging fluid into said cylinder through said first inlet port and means for introducing a stream of

scavenging fluid into said cylinder through said second inlet port.

3. In a two-cycle internal combustion engine, the combination comprising a cylinder provided with two groups of inlet ports and one group of outlet ports, a tubular sleeve having cooperating openings guided for reciprocating movement in said cylinder, a piston guided for reciprocating movement in said sleeve and cooperating with the openings in said sleeve for controlling one group of said inlet ports symmetrically with respect to the lower dead center point of said piston, and means interconnecting said piston and sleeve for controlling the other group of inlet ports asymmetrically with respect to said lower dead center point, and in such a manner that said second group of inlet ports remain open after said first group of said inlet ports has been closed, and means for supplying said first group of inlet ports with a scavenging fluid, and means for supplying said second group of inlet ports with a charging fluid.

4. The combination according to claim 3 in which the ports of each group are circumferentially distributed and in which the second group of inlet ports are adjacent the outlet ports.

5. The combination according to claim 3 in which the ports in each group are circumferentially distributed, and in which the second group of inlet ports are adjacent the outlet ports, all of said inlet ports converging toward a point eccentrically located within the cylinder at the side remote from said outlet ports.

6. In a two-cycle internal combustion engine, the combination comprising a cylinder provided with inlet and outlet ports, a tubular sleeve having cooperating openings and guided for reciprocating movement in said cylinder, a piston guided for reciprocating movement in said sleeve, a crank shaft having a plurality of crank pins and a plurality of connecting rods one of which joins one of said crank pins to said piston and the other of which joins the other crank pins to said sleeve, said piston operating crank pin leading said sleeve operating crank pins by approximately 130 to 180° , whereby said inlet and outlet ports are controlled asymmetrically with respect to the lower dead center point of said piston, the outlet ports being opened sooner with respect to said dead center point than they are closed and the inlet ports being opened later with respect to said dead center point than they are closed.

7. In a two-cycle internal combustion engine, the combination comprising a cylinder provided with two groups of inlet ports and with outlet ports, a tubular sleeve having cooperating openings for controlling one group of inlet ports and said outlet ports and guided for reciprocating movement in said cylinder, a piston guided for reciprocating movement in said sleeve and controlling a second group of said inlet ports and means interconnecting said sleeve and piston in such a manner that the first group of inlet ports and outlet ports are controlled in an asymmetrically timed relationship relative to the passage of the piston through its lower dead center point.

8. In an internal combustion engine, the combination of a cylinder having two groups of inlet ports and one group of outlet ports, the inlet ports of one of said groups having internally projecting mouths, a tubular sleeve having elongated openings circumferentially closely fitting said projecting mouths, guided for reciprocating motion in said cylinder and adapted to control

- said second group of inlet ports, and a piston guided for reciprocatory motion in said sleeve and adapted to open and close said mouths.
9. A two-cycle internal combustion engine comprising in combination, a cylinder, a slide valve in said cylinder, a piston in said slide valve, an inlet and outlet port for said cylinder controlled by said piston and slide valve, and a further inlet port for said cylinder controlled by said piston alone.
10. A two-cycle internal combustion engine comprising in combination, a cylinder, a slide valve in said cylinder, a piston in said slide valve, an inlet and outlet port for said cylinder controlled by said piston and slide valve, a further inlet port for said cylinder controlled by said piston alone, and means drivably connecting said piston and slide valve for opening the first named inlet port shortly after the outlet port has been opened and closing it shortly after the outlet port has been closed, and for opening the second inlet port shortly before the outlet port has been closed and closing it after the outlet port and the first named inlet port have been closed.
11. The combination according to claim 9 in which the inlet ports controlled by the piston and slide valve are arranged opposite to the outlet ports and are adapted to charge the cylinder, and the second named inlet ports controlled by the piston alone are adjacent to said outlet ports and are adapted to scavenge the cylinder.
12. The combination according to claim 9 in which the inlet ports controlled by the piston and slide valve are arranged opposite to the outlet port and are adapted to charge the cylinder and the second named inlet ports controlled by the piston alone are arranged adjacent to said outlet port and are adapted to scavenge the cylinder, the outlet port being substantially radially directed to the axis of the cylinder and the inlet ports being slightly upwardly directed and converge toward a point eccentrically located within the cylinder at the side remote from said outlet ports.
13. A two-cycle internal combustion engine comprising in combination, a cylinder, an outlet port for said cylinder directed radially to the axis of said cylinder, an inlet port for said cylinder slightly upwardly directed at an angle to the axis of the cylinder and arranged opposite to the outlet port, a further inlet port slightly upwardly directed to the axis of the cylinder and located adjacent the outlet port at a slightly lower level than said first inlet port, both of said inlet ports converging towards a point eccentrically located within the cylinder at the side remote from said outlet port, a mouth on said further inlet port projecting inwardly from said cylinder, a tubular slide valve in said cylinder having opposite ports respectively controlling the opposite inlet and outlet ports and having a longitudinal slot straddling the mouth of said further inlet port, a piston in said tubular slide valve controlling the ports in said slide valve and the further inlet port in said cylinder, means drivably connecting the piston with said slide valve, the angular relationship of such connecting means being such that the inlet and outlet ports controlled by the piston and slide valve will be controlled asymmetrically and the inlet port controlled by the piston alone will be controlled symmetrically with respect to the lower dead center point of the piston.
14. A two-cycle internal combustion engine comprising in combination, a cylinder, an outlet port for said cylinder directed radially to the axis of the cylinder, an inlet port for said cylinder slightly upwardly directed at an angle to the axis of the cylinder and arranged opposite to the outlet port, a further inlet port slightly upwardly directed to the axis of the cylinder and located adjacent the outlet port at a slightly lower level than said first inlet port, both of said inlet ports converging toward a point eccentrically located within said cylinder at the side remote from said outlet port, a mouth on said further inlet port projecting inwardly from said cylinder, a tubular slide valve in said cylinder having opposite ports respectively controlling the opposite inlet and outlet ports and having a longitudinal slot straddling the mouth of said further inlet port, a piston in said tubular slide valve controlling the ports in said slide valve and the further inlet port in said cylinder, means drivably connecting the piston with said slide valve, the angular relationship of this connecting means being such that the inlet port controlled by said slide valve will be opened shortly after the outlet port has been opened and will be closed shortly after the outlet port has been closed, and the inlet port controlled by the piston alone will be open shortly before the outlet port has been closed and will be closed shortly after the outlet port and said first main inlet port have been closed, whereby the inlet and outlet ports controlled by said piston and slide valve will be controlled asymmetrically and the inlet port controlled by the piston alone will be controlled symmetrically with respect to the lower dead center point of the piston.
15. A two-cycle internal combustion engine as set forth in claim 13 in combination with means for introducing a stream of charging fluid into said cylinder through said first inlet port, and means for introducing scavenging fluid into said cylinder through said further inlet port.
16. The method of controlling a two-cycle internal combustion engine having two groups of inlet ports and one group of outlet ports, including the steps of opening the outlet ports, opening one group of inlet ports a short time thereafter, closing the outlet ports, closing said first group of inlet ports a short time after said outlet ports have been closed, opening the second group of inlet ports a short time before the outlet ports have been closed and closing said second group of inlet ports shortly before said outlet ports and said first group of inlet ports have been closed.
17. The method of controlling a two-cycle internal combustion engine having two groups of inlet ports and one group of outlet ports, including the steps of controlling one group of inlet ports and said outlet ports asymmetrically with respect to the lower dead center point of the cylinder piston, and controlling the other group of inlet ports symmetrically with respect to the lower dead center point of the cylinder piston.
18. The method according to claim 17 including the steps of introducing a stream of charging fluid through said first group of inlet ports, and a stream of scavenging fluid through said second group of inlet ports.
19. In a two-cycle internal combustion engine, the combination comprising a cylinder provided with inlet and outlet ports, a tubular sleeve having cooperating openings and guided for reciprocatory movement in said cylinder, a piston guided for reciprocatory movement in said sleeve, and means interconnecting said sleeve and piston in such a manner that said inlet and

5 outlet ports are asymmetrically controlled, the outlet ports being opened before the inlet ports with respect to the lower dead center point of the piston and both said inlet and outlet ports being closed at substantially the same time.

20. In a two-cycle internal combustion engine, the combination comprising a cylinder provided with groups of inlet and outlet ports, said outlet ports being radially directed in one side of said cylinder and said groups of inlet ports being axially displaced on the opposite side of said cylinder and directed at an oblique angle to the radius and axis of said cylinder, a tubular sleeve having

cooperating openings and guided for reciprocatory movement in said cylinder, a piston guided for reciprocatory movement in said sleeve, and means interconnecting said sleeve and piston in such a manner that said inlet and outlet ports are asymmetrically controlled, the outlet ports being opened sooner with respect to the lower dead center point of the piston than they are closed, and said inlet ports being opened later with respect to said dead center point than they are closed. 5

ALFRED BOKEMÜLLER.
